United States Patent Office

Des. 208,416
Patented Aug. 29, 1967

208,416

EARTH AUGER

Gustav H. Sudmeier, 13728 S. Normandy,
Gardena, Calif. 90249

Filed Aug. 10, 1966, Ser. No. 3,405

Term of patent 14 years

(Cl. D39—1)

FIG. 3

FIG. 4

FIGURE 1 is a side elevational view of an earth auger, showing my new design;

FIGURE 2 is a top plan view thereof;

FIGURE 3 is a front elevation view thereof; and

FIGURE 4 is a bottom plan view thereof.

The dominant features of my design reside in the portions shown in full lines.

I claim:

The ornamental design for an earth auger, substantially as shown and described.
